ATTORNEY:

UNITED STATES PATENT OFFICE

JOHANN G. PETERSON, OF WEST HARTFORD, CONNECTICUT

ELECTRIC SWITCH

Application filed December 31, 1928. Serial No. 329,570.

My invention relates to electric switches.

It has for its object to provide an improved electric switch, and more particularly an improved switch of the type adapted to control electric heating pads. A further object is to provide an improved switch of the latter type having a swinging actuating member movable progressively in either direction through a plurality of positions to make and break a plurality of circuits, and improved means whereby it is rendered impossible for the operator to retard either the making or breaking of the circuit. Further objects include the provision of improved and simplified switch actuating mechanism, improved and simplified terminals, improved and simplified connecting means for the parts of the switch unit, and improved connecting means for the casing members enclosing the unit, whereby while the effectiveness of the switch is improved its structure is rendered more compact and also substantially simplified and cheapened. These and other objects and advantages of my improved construction will, however, hereinafter more fully appear.

In the accompanying drawing I have shown, for purposes of illustration, two embodiments which my invention may assume in practice.

In this drawing,—

Figure 1 is a plan view of a switch enclosed in its outer casing, the actuating member also being indicated in dotted lines in its various positions;

Fig. 2 is a similar view of the switch with the outer casing member removed to show the switch unit;

Fig. 3 is a similar view but with the other casing member removed;

Fig. 4 is a plan view of the switch unit with one of the insulating plates thereof removed;

Fig. 5 is a plan view of the inside of the other plate;

Fig. 6 is a longitudinal sectional view on line 6—6 of Fig. 1;

Fig. 7 is a transverse sectional view on line 7—7 of Fig. 1;

Fig. 8 is a detail view of the switch actu-

ating and contact carrying member, one combined cam and contact member being removed to facilitate illustration, and

Fig. 9 is a similar view of a modified construction.

In Figs. 1 to 8, I have shown a switch mechanism including cooperating casing members 1 and 2 enclosing the switch unit which is generally designated 3 and has a laterally protruding pivoted actuating member 4 movable about a pivot pin 5 and in a plane between the flat insulating plates 6 and 7 comprised in the unit 3, while the plate 6 carries on its outer surface terminals 8 and 9 and the plate 7 similarly carries terminals 10, 11 and 12, and all of these terminals are adapted to be connected to conductors extending through the opposite ends of the casing members 1 and 2, as shown in Fig. 1.

Referring more particularly to the switch mechanism, it will be noted that each of the plates 6 and 7 has a small conducting plate 13, 13' of substantially rectangular form through which the pivot pin 5 extends and which is suitably attached to the plate, as by rivets 14 at the opposite ends thereof. It will also be noted that each of these plates 13, 13' carries at one side of the pivot pin a series of peaked projections 15, herein three, having oppositely sloping sides and radially disposed close to one another, as indicated in Fig. 5. Associated with the peaked members 15 on the plates 13, 13', which are thus disposed in spaced radially extending series one above the other, is the actuating member 4. As shown herein, this member includes a body portion 16 herein of metal and of substantially U-shape and having inwardly extending abutments 17 at its open end and a small socket 18 at its opposite end communicating with its larger opening. This body 16 is connected by rivets 19, spaced laterally from the socket 18, to superimposed combined contact and cam carrying members 4' above and below the body 16. As shown, each of these members 4' has a single raised and resilient arm 20 carrying a contact 21 on its upper end, and also a raised and resilient body portion 22 carrying a projection 23 similar to one of the projections 15 and adapted to

55

60

65

70

75

80

85

90

95

100

cooperate with one set of said projections. Each of these combined and cam carrying members 4' is herein also provided with an extension 24 bridging over the large opening 5 in the body 16 and having an aperture receiving the pivot pin 5. Moreover, it will be noted that between these projections 24, and on this pivot pin, is carried the inner end of the member 4. Herein it will also be noted 10 that a flat spring 25 is provided which has a rounded end seated in the socket 18 and restricted portions passing therefrom between adjacent protruding portions 26 at the mouth thereof, and larger reversely bowed portions 15 extending longitudinally through the larger opening in the body 16 and provided with curved ends 27 each resting against an opposite side of the member 4 at a point remote from the pin 5. Here, attention is also 20 directed to the fact that, the member 4 having play in a vertical plane relative to its pin 5, lugs in the form of projections 28 are provided nearer the outer end of the member 4 in such position that these projections 28 may 25 engage the insulating plates 6 and 7 and prevent too great vertical movement of the member 4. These projections 28 herein are in the form of upwardly and downwardly struck portions and the member 4 is of sheet metal 30 type, this being a simple and inexpensive construction well adapted to use where a molded-on actuating button is used. It will also be noted that the outer end of the member 4 is provided beyond these projections 28 35 with a slightly raised flat portion 29 adapted to be received in and move within the limits of a slot 30 in the casing member 1, and that the member 4 has molded on its outer end a protruding button 31 of generally 40 acorn shape and adapted to convenient operation.

Cooperating with the switch mechanism described are improved terminal connections 8, 9, 10, 11 and 12 carried on the outside of 45 the switch unit. Of these, the terminals 8 and 9 are carried on the outside of the insulating plate 6 and the terminals 10, 11 and 12 are carried on the outside of the insulating plate 7. Herein it will be noted 50 that the terminal 11 is connected to the plate 7 by rivets 32 which extend through the plate, and perform the additional function of acting as contacts cooperating with the adjacent movable contact 21. The 55 terminal 8 is also attached to the plate 6 by rivets 33 which also similarly act as contacts cooperating with the other movable contact 21. It will also be observed that the connecting plate 18' on the insulating plate 6 is connected by one of its rivets 14 to the terminal 9, thereby providing a permanent connection to the line. It will also be noted that a through connection is always provided between the terminals 10 and 12, a bowed conducting strip 34 extending between these two 60

terminals on the inside surface of the plate 7 and spaced from the edge of the plate 13 carrying the projections 15 and being connected at its ends to said terminals 10 and 12 by rivets 35. Here attention is also directed 70 to the fact that each of the terminals 8, 9, 10, 11 and 12 is provided with an end 36 projecting beyond the end of the insulating plate carrying the terminal in question and bent inward and carrying a binding screw 75 37. Attention is also directed to the fact that each of the plates 6 and 7 is notched on opposite sides of its end, as shown at 38, to permit the passage of these bent terminal ends 36, and also form an extension 39 adjacent to 80 each notch, one of which, on the plate 7, extends between the adjacent ends of the terminals 10 and 11.

In this improved construction, I have also provided improved means for connecting the plates 6 and 7 and holding the parts of the switch unit and mechanism together. Herein it will be noted that at opposite ends of the switch unit and in alignment with the pivot pin 5, spacing members 40 are provided between the plates 6 and 7. Each of these members 40 has flanges 41 adapted to engage the inner faces of the plates 6 and 7 and reduced portions 42 extending through those plates and having their outer ends bent 90 or spun over washers 43 seated on the outer surfaces of the plates. Thus it will be noted that with the switch mechanism arranged as described relative to the pivot 5, the parts of the switch unit are effectually spaced and 100 firmly clamped together. Moreover, it will be noted that the spacing and connecting means described are wholly independent of the electrical connections and the plates 13, 13' and that they have no function in 105 connection with the operating member 4, the limits of movement of the latter being established by the slot 30. In my improved construction, however, these members 40 are utilized as a part of the connecting means for 110 the casing members 1 and 2, each member 40 being internally threaded and adapted to receive in its opposite ends short screws 44 receivable in suitable registering apertures 115 in the casing members 1 and 2, as shown in Fig. 6.

Here it will also be noted that the casing members 1 and 2 and the unit are so constructed and arranged as to position one another and greatly facilitate assembly. More particularly, it will be observed that the casing members 1 and 2 are provided around the apertures of the screws 44 with raised flat surfaces 45 which engage the washers 43. It will also be noted that the casing members 120 1 and 2 are provided with raised flat lugs 46 on the side of the same opposite the slot 30, and that these are adapted to engage the outer flat faces of the plates 6 and 7 adjacent the edges of the latter, and thereby assist in 125 130

locating the unit. It will also be observed that, to assist in assembly, the casing member 2 is provided at a point opposite its lug 46 with a lug 47 of considerably greater height and adapted to be received in a correspondingly shaped recess in the edge of the plate 7 when the unit is placed in the member 2 with the operating handle 4 projecting to the right, but in all other positions to prevent the insertion of the unit in the casing member 2. Thus it will be observed that the process of assembly is greatly facilitated, it only being necessary for the assembler to bring the notch 48 into position to receive the long projection 47 and then to place the casing member 1, having the cover slot 30, in position with the slot in its obviously proper position over the projecting handle 4.

In the operation of the assembled device, assuming that the switch is in the "off" position illustrated in full lines in Fig. 1, it will be evident that as the operating member 4 is moved downward to the successive dotted line positions shown, the desired low, medium and high heat positions of the contact parts will be successively occupied. In each movement of the actuating member, not only will the spring portions of the members 4' be pressed together by the engagement of their projections 23 with a cooperating projection 15 to impart a swinging movement when the peaks of the projections 15 have been passed, but the spring 25 will be compressed by the movement of the member 4 about its pivot, in such manner as to impart a snap action which cannot in any way be retarded by the operator. Thus, by the provision of the two snap actuating spring means I produce a structure wherein not only by reason of the resilient cam construction an entirely satisfactory snap action will be produced in ordinary operation, but a construction wherein this action is even further speeded up and, even should the operator be ignorant or careless, or even attempt to make trouble, it is made impossible for the operator to delay the making or breaking of the circuit in an objectionable manner. It will, of course, be evident that during operation the switch terminals will be connected to the line and the pad conductors in a usual manner, and that current will flow to the switch through the terminal 9 and connecting plate 13, while a permanent through connection is provided by the terminals 10 and 12 and the bowed conducting strip 34. As regards current distribution, it will also be understood that it will be distributed in a usual manner by the contacts 21, one of which will engage the rivets 32 on the plate 7, while the other will engage the rivets 33 on the plate 6, the arrangement of these contacts 32 and 33 being such that in the "off" position neither set is engaged by a contact 21, while as the contacts 21 swing toward "high" position one of

them engages one contact of one set and the other next engages one contact of the other set, and each finally engages one contact of each set, in a well known manner.

In Fig. 9 I have illustrated a modified construction wherein the spring 25 is omitted. It will be observed that the combined cam and contact carrying members 4' are constructed identically as heretofore and that the only difference, in addition to the omission of the spring, is in the shape of the body member 16. This, in this construction, has no socket 18 and is also provided with a smaller opening 49 at the left thereof and one which is adapted to fit the end of the member 4 and has projections 50 on opposite sides of the latter which convey the motion thereof directly to the body without the intermediary action of the spring as in the previous construction. Obviously, the mechanism previously described will permit the substitution of a member 4' of the construction shown in Fig. 9 for a member shown in Fig. 8, and will then produce an effective device though lacking the feature of the automatic control of the making and breaking provided by the previously described construction.

As a result of my improvements, it is made possible in my preferred construction to provide a switch mechanism of the type set forth which is wholly independent of the operator, i. e., one in which even if the operator is careless, ignorant, or malicious, and moves the switch operating member in a slow and improper manner, the contacts will be operated with the desired quick movement. Attention is, moreover, directed to the simplification and cheapening of manufacture made possible by this improved construction, a minimum of metal being used and the various parts used being of a type which may be very cheaply provided. Thus, for example, the cam plate structure is reduced substantially in size and the amount of metal required to produce the cam plates and terminals including the through connection, is substantially reduced. It will also be noted that a more compact construction is provided enabling a more thin unit to be produced and one of generally smaller dimensions adapted to be more conveniently held in the hand and operated. Through the use of my combined unit spacing and casing attachment means, it is also possible to simplify and cheapen the construction, especially of the casing members, while permitting more ready access to the unit whenever desired, all obstructions on the casing adjacent the terminals being eliminated. Through my improved cooperating unit and casing members, the structure of the latter is also simplified and improved in such manner as not only to reduce its cost but facilitate manufacture and assembly. These and other

advantages of my construction will be clearly apparent to those skilled in the art.

While I have in this application described two embodiments which my invention may assume in practice, it will be understood that these embodiments are chosen for illustrative purposes and that my invention may be further modified and embodied in various other forms without departing from its spirit or 10 the scope of the appended claims.

What I claim as new and desire to secure by Letters Patent is:—

1. An electric switch having swinging contact carrying and actuating members, and 15 snap actuating means for the former operative by the latter including snap actuating means and co-operating snap actuating means operative irrespective of the rate of movement of said actuating member and 20 having an additional spring.

2. An electric switch having swinging contact carrying and actuating members, and a plurality of co-operating snap actuating means for the former operative by the latter 25 and including combined snap actuating and indexing means and co-operating snap actuating means operative irrespective of the rate of movement of said actuating member and having an additional spring tensioned 30 by said actuating member and released by said combined snap actuating and indexing means.

3. An electric switch having swinging contact carrying and actuating members, a plurality of co-operating snap actuating means 35 for the former operative by the latter, and another resilient snap actuating means having an additional spring likewise tensioned by said actuating member and released for 40 operation upon operation of said plurality of means.

4. An electric switch having a contact carrying member, co-operating movable and stationary contacts, a pivoted actuating member, snap actuating means actuated by said actuating member and actuating said contact carrying member, and resilient co-operating snap actuating means for actuating said contact carrying member irrespective of 45 the rate of movement of said actuating member and having an additional spring tensioned by movement of said actuating member.

5. An electric switch having a contact 55 carrying member, co-operating movable and stationary contacts, a pivoted actuating member, snap actuating means actuated by said actuating member when the latter is swung in either direction and actuating said contact carrying member with a snap action in either direction, and co-operating spring means operative irrespective of the rate of movement of said actuating member actuating said contact carrying member with a 60 snap action in either direction and tensioned

by said actuating member when swung in either direction.

6. An electric switch having a swinging contact carrying member and a pivoted actuating member, and snap actuating means for the former including a resiliently mounted actuating member movable with said contact carrying member toward and from the same as said pivoted actuating member is swung and an additional spring actuating member actuating said contact carrying member with a snap action irrespective of the rate of movement of said actuating member and tensioned upon movement of said pivoted actuating member. 75

7. An electric switch having a swinging contact carrying member and also a pivoted actuating handle, and snap actuating means including a plate spring carried by and actuating said contact member and movable toward and from the same as said handle is swung, and a co-operating spring member actuating said contact member and tensioned by said handle and operative irrespective of the rate of movement of the latter. 80

8. An electric switch having a swinging contact carrying member and also a pivoted actuating handle, and snap actuating means including a plate spring actuating said contact member and movable laterally therewith and toward and from the same as said handle is swung in either direction, and a co-operating spring member actuating said contact carrying member and tensioned by said handle as it swings in either direction and operative irrespective of the rate of movement thereof. 90

9. An electric switch having swinging contact carrying and actuating members, snap actuating means for the former member including a series of projections and a co-operating resiliently mounted projection engageable with said projections and actuated by the latter member, and co-operating resilient snap actuating means having an additional spring tensioned by said actuating member and actuating said contact carrying member and operative to inhibit retardation of the circuit making and breaking movement. 100

10. An electric switch comprising an insulating base having means for supporting a switch mechanism, stationary contacts thereon, and a series of hills and valleys thereon, and a switch mechanism mounted on said supporting means and having an operating lever, a movable pole piece with a spring contact at one end of said pole piece adapted to engage said stationary contacts and a spring arm rigidly connected with said spring contact and at the other end of said pole piece adapted to engage said hills and valleys, and a spring tensioned by said operating lever and actuating said pole piece as said spring contact passes over said hills. 115

11. An electric switch comprising an insu- 120

lating base having a shaft support, stationary contacts and a series of hills and valleys spaced from said support in arcuate relation thereto, and a unitary switch mechanism having a shaft, an actuating lever on said shaft, a movable pole piece on said shaft and comprising two spring arms provided respectively with contacts and a boss for engaging said hills and valleys, and a biasing spring surrounding said shaft and connecting said lever and said pole piece.

12. An electric switch having swinging contact carrying and actuating members, snap actuating means for the former member including a series of projections and a co-operating resiliently mounted projection actuated by the actuating member in either direction of movement thereof, and resilient for actuating means actuating said contact member irrespective of the rate of movement of said actuating member including an additional spring tensioned by said actuating member in either direction of movement thereof and acting to throw said contact member with a snap action.

13. An electric switch having swinging contact carrying and actuating members, snap actuating means for the former member including a series of projections and a co-operating resiliently mounted projection actuated by said actuating member and carried with said contact carrying member and movable toward and from the same as said resiliently mounted projection moves over said projections, and co-operating resilient actuating means including an additional spring tensioned by said actuating member and acting to throw said contact carrying member with a quick snap action irrespective of the rate of movement of said actuating member.

14. An electric switch having coaxial swinging contact carrying and actuating members, co-operating movable and stationary contacts, indexing mechanism comprising a single reversely operative indexing member movable with said contact carrying member in either direction and co-operating indexing means engageable by said movable member, and operative connections between said actuating member, movable member, and contact carrying member including an additional spring and operative to swing the contact carrying member with a snap action irrespective of the rate of movement of said actuating member.

15. An electric switch having coaxial swinging contact carrying and actuating members, co-operating movable and stationary contacts, indexing mechanism comprising a single member movable with said contact carrying member in either direction and co-operating indexing means engageable by said movable member, and operative connections between said actuating member, movable member, and contact carrying member in-

cluding an additional spring and operative to swing the contact carrying member with a snap action irrespective of the rate of movement of said actuating member, said co-operating indexing means comprising a series of spaced projections having oppositely sloping sides, and said member co-operating therewith being resiliently mounted and also swinging said contact carrying member laterally as it moves down each sloping side.

16. An electric switch having stationary and movable contact means for controlling a plurality of circuits, a pivoted actuating member for said movable contact means, indexing means for said movable contact means having a member initially movable with the latter to released position by said actuating member, and snap actuating means for said movable contact means tensioned by said actuating member and operative automatically independently thereof when said indexing member is in released position.

17. An electric switch having stationary and movable contact means for controlling a plurality of circuits, a pivoted actuating member for said movable contact means, a series of spaced stationary projections, a co-operating resiliently mounted projection actuated by said actuating member and actuating said movable contact means both as it moves up and down each projection, and co-operating snap actuating means for said movable contact member tensioned by movement of said actuating member and automatically operative independently thereof when said co-operating projection passes beyond the top of each stationary projection.

18. An electric switch having stationary and movable contact means for controlling a plurality of circuits, a pivoted actuating member for said movable contact means movable in a short arc reversely between predetermined travel limits to control said circuits and having an off position at one travel limit and a plurality of on positions between said limit and the other limit thereof, a series of spaced stationary projections, a co-operating resiliently mounted projection actuated by said actuating member and actuating said movable contact means both as it moves up and down each projection, and co-operating snap actuating means for said movable contact member tensioned by movement of said actuating member and automatically operative independently thereof when said co-operating projection passes beyond the top of each stationary projection.

19. In an electric switch, insulating members, connecting means for each end thereof, a series of spaced stationary cams carried by one of said members within said members and insulated from said connecting means, stationary contacts within said members having contacts carried by the other insulating member, and switch mechanism pivotally mount-

- ed between said members intermediate the ends thereof having a resiliently mounted co-operating cam member engageable successively with said spaced stationary cams, movable contact means engageable with said stationary contacts and actuated successively with a snap action by said co-operating cam member as it moves over said stationary cams, an actuating member for said co-operating 5
- cam operable from the exterior of said insulating members, and spring means tensioned by said actuating member and actuating said movable contact means.
20. In an electric switch, spaced insulating plates, connecting means for each end thereof, terminals on the outside of said plates, cam plates carried on the inner surfaces of said insulating plates spaced between said connecting means and insulated from the latter, and one insulated from said terminals and the other connected to one of the latter, stationary contacts also on the inner surfaces of said plates and connected to certain other terminals, and switch mechanism pivotally 20
- 25 mounted between said plates intermediate the ends thereof having resilient co-operating cam members co-operating with different cam plates, movable contacts actuated by said co-operating cam members and co-operating 30
- 35 with said stationary contacts, and an actuating member having operative connections for actuating said co-operating cam members and movable contacts and an operative end projecting from between said insulating plates.
21. In an electric switch, spaced insulating plates, connecting means for each end thereof, terminals on the outside of said plates, cam plates carried on the inner surfaces of 40
- 45 said insulating plates between said connecting means and insulated from the latter, and one insulated from said terminals and the other connected to one of the latter, stationary contacts also on the inner surface of said plates and connected to certain other terminals, and switch mechanism pivotally mounted between said plates intermediate the ends thereof having resilient cooperating cam members co-operating with different cam 50
- 55 plates, movable contacts actuated by said co-operating cam members and co-operating with said stationary contacts, an actuating member for said co-operating cam members and movable contacts and projecting from between said insulating plates, and actuating connections for said movable contacts having spring means tensioned by said actuating member.
22. A switch actuating member comprising 60
- a body member having a lateral opening therein and a recess communicating with said opening, oppositely extending resilient contact and actuating members on one face of said body member, means likewise carried by 65
- the latter presenting a pivot bearing there- for, an actuating handle having one end receivable in said lateral opening and movable relative to either wall thereof, a pivot member extending through said end and journaled in said pivot bearing, and a spring having a portion seated in said communicating recess and also projecting portions between said walls and handle and acting on the opposite sides of said handle.
23. A switch actuating member comprising 75
- 70 a body member having a lateral opening therein, oppositely extending resilient contact and actuating members on one face of said body member, means likewise carried by the latter presenting a pivot bearing therefor, an actuating handle having one end projecting into said lateral opening and engageable with the opposite walls thereof, and a pivot pin journaled in said pivot bearing on said body member and also extending through the end of said handle disposed in said opening.
24. An electric switch comprising a switch unit having spaced insulating members and switch mechanism therebetween, enclosing 80
- 85 casing members having provision for enabling operation of said switch mechanism, and means for separately connecting said casing members to said unit.
25. An electric switch comprising a switch unit having spaced insulating members, switch mechanism therebetween, and connecting means for said plates, enclosing casing members having provision for enabling operation of said switch mechanism, and means 90
- 95 connecting said casing members to said connecting means.
26. An electric switch comprising cooperating insulating plates, a switch mechanism therebetween, cooperating casing members enclosing said plates and enabling operation of said mechanism, means connecting said plates together including threaded members, and means operable from the exterior of said casing members and threaded in said threaded members for connecting said casing members.
27. A through switch comprising insulating plates, a switch mechanism therebetween, terminals for said switch mechanism on the outside surfaces of said plates and having their outer ends extending over the adjacent ends thereof and bent inward, and binding screws carried on said inwardly bent ends.
28. A through switch comprising spaced 100
- 105 insulating members, a switch mechanism therebetween, terminals for said switch mechanism on the outside surfaces of said members, and a connection between certain of said outside terminals disposed between said members and so disposed as to be insulated from the other terminals and said switch mechanism.
29. A through switch comprising spaced 110
- 115 insulating plates, a switch mechanism there-
- 120
- 125
- 130

between, terminals for said switch mechanism on the outside surfaces of said plates, a connection between certain of said outside terminals disposed between said plates, and means attaching said connection and its terminals to its plate also electrically connecting said connection and terminals.

30. In a through switch, co-operating insulating members, terminals thereon, switch mechanism between said members connected to certain of said terminals and having co-operating contacts and an operating member projecting from between said members and movable longitudinally thereof, and a through connection disposed between the adjacent faces of said insulating members and connecting certain of said terminals.

31. In a through switch, co-operating insulating members, terminals thereon, switch mechanism between said members connected to certain of said terminals and having co-operating contacts and a pivoted operating member projecting from between said members and movable longitudinally thereof, and a through connection disposed between the adjacent faces of said insulating members and between the pivot and free end of said operating member and connecting certain of said terminals.

32. In a through switch, co-operating insulating members, terminals thereon, switch mechanism between said members connected to certain of said terminals and having co-operating contacts, a pivoted operating member projecting from between said members and movable longitudinally thereof, and contact actuating mechanism including a series of stationary cams carried by one of said insulating members and a co-operating resilient cam movable by said operating member, and a through connection connecting certain of said terminals disposed between the adjacent faces of said insulating members and carried by one of the same.

33. In an electric switch, co-operating insulating members, connecting means therefor, a cam plate insulated from said connecting means and carried by one member, stationary contacts also carried by one of said insulating plates, and a switch mechanism between said insulating plates and having a resilient contact actuating portion engaging said cam plate and movable contact means actuated thereby and engaging said contacts.

34. In an electric switch, spaced insulating plates, connecting means therefor, a cam plate carried on one plate and spaced from said connecting means, means independent of said connecting means for connecting said cam plate to said insulating plate, stationary contacts also carried by one of said insulating plates, and switch mechanism between said insulating plates and having movable contact means and a resilient movable con-

tact actuating portion engaging said cam plate.

35. In an electric switch, spaced insulating plates, connecting means therefor, a cam plate insulated from said connecting means and carried on one plate, contacts also carried by the latter plate, and a switch member movable between said insulating plates having a resilient portion engaging said cam plate and a contact engaging said contacts.

36. In an electric switch, spaced insulating plates, connecting means at their opposite ends, spaced cam plates carried on the inside thereof and insulated from said connecting means, contacts carried on the inside surfaces of said insulating plates, and electrically connected conducting members having resilient portions engaging said cam plates and contacts engaging said contacts.

37. In a switch, spaced insulating members contacts therebetween, a swinging body member between said members carrying a co-operating contact, actuating mechanism between the body member and one of said plates, an actuating member pivoted on said body and movable toward and from said actuating mechanism, and means between one of said plates and said actuating member inhibiting conflict between the latter and said mechanism.

38. In a switch actuating mechanism, a body having an opening in one side of the same, a combined contact and cam member thereon having an axial opening therein, an actuating member received in said first mentioned opening and having an opening registering with said axial opening, and a pivot pin extending through said registering openings.

39. In a switch actuating mechanism, a pivoted contact carrying body member having a lateral opening therein and carrying a resilient member extending over said opening, an actuating member extending into and pivoted in said opening, and means for swinging said body member upon movement of said actuating member about its pivot.

40. A switch actuating member comprising a pivoted body member having a lateral opening and carrying a contact member and a resilient actuating member, an actuating handle pivoted in said lateral opening and movable relative to one wall thereof, and a spring between said handle and wall compressed by movement of the former and operative to move the latter.

41. A switch actuating member comprising a pivoted body member having a lateral opening and carrying a contact member and a resilient actuating member, an actuating handle pivoted in said lateral opening and movable relative to either wall thereof, and a spring seated in said body and having bowed portions engaging opposite sides of said handle.

42. In combination, a switch unit comprising insulating plates and switch mechanism therebetween and terminals at the ends of said plates, and casing members longitudinally divided along meeting faces lying substantially between said plates enclosing said unit while enabling operation of said switch mechanism and having unobstructed end areas leading to said terminals.
43. In combination, a switch unit comprising insulating plates and switch mechanism therebetween and terminals at the ends of said plates, and casing members enclosing said unit while enabling operation of said switch mechanism, said casing members having positioning means engaging said plates and one of said plates and casing members having interlocking means requiring assembly in a predetermined position.
44. An electric switch having coaxial swinging contact carrying and actuating members, co-operating movable and stationary contacts for making and breaking a plurality of circuits as said contact carrying member is swung in either direction, indexing mechanism comprising a reversely operative indexing member movable with said contact carrying member in either direction into different operative positions of the latter, co-operating indexing means engageable by said movable indexing member in said different operative positions, and spring means normally holding said member and means in engagement, means operative upon actuation of said actuating member for releasing said movable indexing member from said co-operating indexing means, and means operative upon actuation of said actuating member in either direction including operative connections between said actuating member, movable member, and contact carrying member, and including also an additional spring, for swinging said contact carrying member with a snap action irrespective of the rate of movement of said actuating member.
45. An electric switch having coaxial swinging contact carrying and actuating members each operative reversely, co-operating movable and stationary contacts for making and breaking a plurality of circuits as said contact carrying member is swung in either direction, indexing mechanism for said member comprising a reversely operative indexing member movable therewith in either direction into different positions and also angularly with respect to the planes of movement of said member out of and into different indexing positions, co-operating indexing means engageable by said movable indexing member in different indexing positions in different positions of said contact carrying member, and spring means normally holding said indexing member and co-operating indexing means in engagement, means operative upon actuation of said actuating member in either direction for moving said movable indexing member angularly with respect to the planes of movement of said contact carrying member to disengage said movable indexing member while tensioning said spring and free said movable member for reengagement by said spring with said co-operating indexing means in a new indexing position, and means operative upon actuation of said actuating member in either direction including operative connections between said actuating member, movable indexing member, and contact carrying member, and also including an additional spring, for swinging said contact carrying member with a snap action irrespective of the rate of movement of said actuating member.
46. An electric switch having coaxial swinging contact carrying and actuating members, co-operating movable and stationary contacts for making and breaking a plurality of circuits as said contact carrying member is swung in either direction, indexing mechanism for said member comprising a reversely operative indexing member movable therewith in either direction when said member moves into different operative positions and also angularly with respect to the planes of movement of said contact carrying member out of and into indexing position, co-operating indexing means engageable by said movable indexing member in different indexing positions in different operative positions of said contact carrying member, and spring means normally holding said movable indexing member and co-operating indexing member in engagement, and means operative upon actuation of said actuating member in either direction including operative connections between said actuating member, movable indexing member, and contact carrying member, and also an additional spring, for moving said movable indexing member out of indexing position while tensioning the spring means thereof, swinging said contact carrying member and movable indexing member with a snap action irrespective of the rate of movement of said actuating member, and freeing said movable indexing member for reengagement with said co-operating indexing means in a new indexing position.
47. An electric switch having coaxial swinging contact carrying and actuating members having swinging contact carrying and actuating portions disposed on opposite sides of the axis thereof, co-operating movable and stationary contacts for making and breaking a plurality of circuits as said contact carrying member is swung in either direction, indexing mechanism for said contact carrying member comprising a reversely operative indexing member movable with said contact carrying member in either direction when said last mentioned member moves into different operative positions and also mov-

able toward and from the planes of movement of said member in different indexing positions, co-operating indexing means engageable by said movable member in different indexing positions in different operative positions of said contact carrying member, and means operative upon actuation of said actuating member in either direction for moving said movable indexing member to-
10 ward and from said planes including a cam movable about said axis and spring means normally holding said movable indexing member and co-operating indexing means in engagement and tensioned upon movement of
15 said actuating member, and means operative upon actuation of said actuating member in either direction including operative connections between said actuating member, movable member, and contact carrying member,
20 and also an additional spring, for swinging said contact carrying member with a snap action irrespective of the rate of movement of said actuating member.

48. An electric switch having stationary
25 and movable contact means for controlling a plurality of circuits, a pivoted actuating member for said movable contact means disposed coaxially with said movable contact means, indexing mechanism for said movable contact means actuated upon operation of said actuating member having indexing means, a co-operating reversible indexing member movable relative thereto about the axis of said actuating member and angularly
30 with respect to the planes of movement of said movable contact means to release the latter and also movable with said movable contact means into different operative positions therewith, mechanism operative upon actuation of said actuating member in either direction including cam means movable about said axis for moving said movable indexing member angularly with respect to the planes of movement of said movable contact means to
35 release the latter and said movable member from said indexing means and spring means tensioned by said cam means for returning said movable indexing member into indexing position in different operative positions
40 of said movable contact means, and means operative upon actuation of said actuating member in either direction and including operative connections between said actuating member, movable member, and movable contact means, and also an additional spring,
45 for swinging said movable contact means with a snap action irrespective of the rate of movement of said actuating member when said movable indexing member is in released
50 position.

In testimony whereof I affix my signature.
JOHANN G. PETERSON.

CERTIFICATE OF CORRECTION.

Patent No. 1,894,225.

January 10, 1933.

Johann G. Peterson.

It is hereby certified that error appears in the printed specification of the above numbered patent requiring correction as follows: In the drawing, the Fig. 1, should appear as shown below instead of as shown in the patent:

Fig. 1.

Page 3, line 54, for "provided" read "provided"; page 4, line 84, claim 7, for "incuding" read "including"; page 5, line 18, claim 12, strike out the word "for" and insert the same before "actuating" in line 19; page 6, line 33, claim 20, for "operative" read "operating"; page 7, line 85, claim 37, after "members" insert a comma; and that the said Letters Patent should be read with these corrections therein that the same may conform to the record of the case in the Patent Office.

Signed and sealed this 16th day of May, A. D. 1933.

M. J. Moore.

(Seal)

Acting Commissioner of Patents.
